Plant 8,879

3

flower and peduncle are oriented approximately at right angles to the stem.

Type.—Single.

Shape.—Not completely round, only weak lobes.

Diameter 50-55 mm (comparatively small).

Color.—Upper (inner) surface at opening: Between

83 A and 79 A. Under (outer) surface at opening:

83 B. Upper (inner) surface at pollen maturity: 83

A-B. Under (outer) surface at pollen maturity: 83

C. Throat (inner surface): Light violet, with dark net-shaped veining.

Peduncle length.—20-25 mm.

4

Peduncle color.—Medium green, with a small amount of anthocyanin near the base of the flower.

Reproductive organs.—Pistil: 1 green. Stammer: 5, fertile. Anther: Bluish white. Filament: White to light violet.

Resistance: Very good resistance to rain and good heat tolerance.

It is claimed:

1. A new and distinct cultivar of Petunia plant named Cas 1, as illustrated and described.
